UNITED STATES PATENT OFFICE

118,410

DESIGN FOR A COMBINED BOOK END AND PENCIL HOLDER OR SIMILAR ARTICLE

Gregory S. Dolgorukov, Detroit, Mich.

Application September 26, 1938, Serial No. 80,083

Term of patent 14 years

To all whom it may concern:

Be it known that I, Gregory S. Dolgorukov, a citizen of the United States, residing at Detroit, county of Wayne, State of Michigan, have invented a new, original, and ornamental Design for Combined Book Ends and Pencil Holders or Similar Articles, of which the following is a specification, reference being had to the accompanying drawing, forming a part thereof.

The figure is a perspective view of a combined book end and pencil holder or similar article, showing my new design.

I claim:

The ornamental design for a combined book end and pencil holder or similar article, as shown.

GREGORY S. DOLGORUKOV.
